Application May 6, 1947, Serial No. 746,207

5 Claims. (Cl. 232—17)

1

This invention relates to a box, and more particularly to a letter box of the type employed for domestic use.

The primary object of the invention is to protect letters, parcels and the like from the elements while they are awaiting collection.

Another object is easily and quickly to gain access to the contents of the box, and to enable the access opening of the box to be easily and quickly closed and sealed against the elements.

The above and other objects may be attained by employing this invention which embodies among its features a box comprising a rectangular back, a bottom at the lower end of the back, a front wall extending upwardly from the bottom in spaced relation to the back, side walls joining the back, bottom and front wall, the upper edge of the front wall terminating intermediate the ends of the back, the front edges of the side walls inclining toward the back as they recede from the upper edge of the front wall and defining with the upper edge of the front wall an access opening for the box, a cover for the access opening slidably longitudinally over the inclined edges of the side walls and the front wall, and means yieldingly to hold the cover in contact with the box.

Other features include a top for the box, an outwardly and downwardly inclined flange at the front edge of the top of the box for overhanging the cover when the latter is in closed position in order to exclude the elements from the box, arms pivoted adjacent the lower forward edges of the side walls, means projecting laterally from the cover and engaging the arms, and means yieldingly urging the arms against the cover-engaging means, yieldingly to urge the cover against the box.

In the drawings,

Figure 1 is a perspective view of a box embodying the features of this invention,

Figure 2 is an enlarged fragmentary side view of the box showing the upper ends of the arms and the lower end of the cover, with the latter in elevated position,

Figure 3 is a fragmentary sectional view taken substantially along the line 3—3 of Figure 1,

Figure 4 is a longitudinal sectional view taken substantially along the line 4—4 of Figure 1, and

Figure 5 is a fragmentary sectional view taken substantially along the line 5—5 of Figure 1.

Referring to the drawings in detail, this improved box comprises a back 10, from the lower edge of which projects forwardly a bottom 11 and projecting upwardly from the forward edge of the

2

bottom 11 in spaced parallel relation to the back 10 is a front wall 12. As illustrated in Figure 4, the bottom 11 preferably lies perpendicular to the back 10 though it is to be understood that the bottom may incline upwardly or downwardly with relation to the back according to the desires of the maker.

Joining the back 10, bottom 11 and front wall 12 are side walls 13, the upper ends of which are also joined to a top wall 14 carrying, at its forward edge, a downwardly and outwardly inclined flange 15, the purpose of which will be more fully hereinafter explained. While the wall 14 is shown as extending perpendicular to the back wall 10 and parallel to the bottom 11, it, too, may be inclined upwardly or downwardly as it recedes from the back 10, according to the desires of the maker. As illustrated in Figure 4, the front wall 12 terminates at a point intermediate the upper and lower ends of the back 10 which is preferably rectangular in plan, and formed at the upper edge of the front wall is an inturned flange or bead 16. The front edges of the side walls 13 which extend between the flange 16 at the upper edge of the front wall 12 and the underside of the top 14 are inclined rearwardly, as at 17, as they recede from the upper edge of the front wall 12. The inclined edges 17 of the side walls 13, the forward edge of the top 14 and the upper edge of the bottom 12 cooperate to define an access opening through which articles such as letters, parcels and the like may be introduced into the box, or removed therefrom.

In order to close the access opening, and at the same time permit the uncovering thereof, I provide a cover 18 which comprises a rectangular sheet of metal provided along opposite side edges with perpendicular flanges 19 forming guide flanges which partially overlie the side walls 13 adjacent their forward edges. Extending outwardly from the lower edge of the rectangular cover 18 is a flange 20 to which a suitable handle or pull 21 is fixed in any suitable manner. Extending outwardly from each side flange 19 near its lower end is a guide member 21, and fixed to each flange and extending through its respective guide member 21 is a laterally extending lug 22, the purpose of which will be more fully herein-after explained. The cover 18 is of an area easily to cover the access opening defined by the front edge of the top 14, the upper edge of the front wall 12 and the front inclined portions of the edges of the side walls 13, and the front wall 12 is of an area at least equal to the area of the cover 18 so that the latter, when moved down-

wardly to clear the access opening, will be supported against the front wall, as illustrated in Figure 4.

In order to hold the cover in contact with the box when in either access opening or closing position or in closing position, I secure adjacent the lower edge of each side wall 13 near the front wall 14 a suitable bracket 23 in which is pivotally supported, as at 24, an upwardly extending arm 25. Each arm 25 is curved toward the back 10 as it recedes from the pivot point thereof, and is provided adjacent its upper end with a hook 26 which is adapted to engage the lug 22 on its respective side of the box when the cover 18 is in closed position. Surrounding each pivot 24 in concentric relation therewith is a helical spring 27, one arm 28 of which bears against a portion of the bracket 23, while the opposite arm 29 of the spring 27 bears against its respective arm 25 in order yieldingly to urge the free ends of the arms toward the back 10. It will thus be seen that when the arms 25 bear against the lugs 22 under the influence of the springs 27, the cover 18 will be yieldingly held against the box. In order to limit the downward movement of the cover over the front 12 and avoid contact of the lugs 22 with the brackets 23, each arm 25 is cut away, as at 30, along its rear edge to form a stop 31.

In use, it will be understood that the back 10 is screwed, or otherwise attached to a vertical support, with the access opening of the box upwardly. Assuming that the cover is in closed position, it will be evident that the upper edge thereof will lie beneath the flange 15 of the top 14 to form a water-tight junction with the cover while the side flanges 19 form water-tight junctions with the side walls 13 of the box. Consequently, the contents of the box will be protected from the elements. At the same time, when it is desired to gain access to the contents of the box, the handle or pull 21 is grasped and the cover moved downwardly into the position illustrated in Figure 4, thus uncovering the access opening.

While in the foregoing there has been shown and described the preferred embodiment of this invention, it is to be understood that minor changes in the details of construction, combination and arrangement of parts may be resorted to without departing from the spirit and scope of the invention as claimed.

Having thus described my invention, what I claims as new is:

1. A box comprising a rectangular back; a bottom at the lower end of the back; a front wall extending upwardly from the bottom in spaced relation to the back; side walls joined to the back, bottom and front wall; the upper edge of the front wall terminating intermediate the ends of the back; the front edges of the side walls inclining toward the back as they recede from the upper edge of the front wall and defining with the upper edge of the front wall an access opening for the box; a cover for the access opening slidable longitudinally over the inclined edges of the side walls and the front wall; and means yieldingly to hold the cover in contact with the box.

2. A box comprising a rectangular back; a bottom at the lower end of the back; a front wall extending upwardly from the bottom in spaced re-

lation to the back; side walls joined to the back, bottom and front wall; the upper edge of the front wall terminating intermediate the ends of the back; the front edges of the side walls inclining toward the back as they recede from the upper edge of the front wall and defining with the upper edge of the front wall an access opening for the box; a cover for the access opening slidable longitudinally over the inclined edges of the side walls and the front wall; guide flanges along opposite side edges of the cover adapted partially to overlie the side walls; and means cooperating with the guide flanges yieldingly to hold the cover in contact with the box.

3. A box comprising a rectangular back; a bottom at the lower end of the back; a front wall extending upwardly from the bottom in spaced relation to the back; side walls joined to the back, bottom and front wall; the upper edge of the front wall terminating intermediate the ends of the back; the front edges of the side walls inclining toward the back as they recede from the upper edge of the front wall and defining with the upper edge of the front wall an access opening for the box; a cover for the access opening slidable longitudinally over the inclined edges of the side walls and the front wall; an arm pivoted adjacent the lower end of each side wall; a lug projecting laterally from each side of the cover; and means yieldingly to hold the arms against the lugs and the cover against the box.

4. A box comprising a rectangular back; a bottom at the lower end of the back; a front wall extending upwardly from the bottom in spaced relation to the back; side walls joined to the back, bottom and front wall; the upper edge of the front wall terminating intermediate the ends of the back; the front edges of the side walls inclining toward the back as they recede from the upper edge of the front wall and defining with the upper edge of the front wall an access opening for the box; a cover for the access opening slidable longitudinally over the inclined edges of the side walls and the front wall; guide flanges along opposite side edges of the cover adapted partially to overlie the side walls; a lug projecting laterally from each side flange; an arm pivotally supported adjacent the lower end of each side wall near the front wall; and means yieldingly to hold the arms against the lugs and the cover against the box.

5. A box comprising a rectangular back; a top at the upper end of the back; a front wall extending upwardly from the bottom in spaced relation to the back; side walls joining the back and front wall with the top and bottom; the upper edge of the front wall terminating intermediate the upper and lower ends of the back; the front edges of the side walls inclining rearwardly as they recede from the upper edge of the front wall and defining with the upper edge of the front wall and the front edge of the top a rectangular access opening for the box; a cover for the access opening slidable over the inclined front edges of the side walls and the front wall; means yieldingly to hold the cover in contact with the box; and a downwardly and forwardly inclined flange at the forward edge of the top for cooperation with the cover to form a water-tight junction therewith when the cover is in a position to close the access opening.

DON A. BEADELL.
